United States Patent Office

Des. 208,487
Patented Sept. 5, 1967

208,487

DUST PAN

Mel Appel, 9 Nottingham Road, Livingston, N.J. 07039,
and Martin Schnur, St. Cloud One, West Orange, N.J.
07052

Filed Nov. 23, 1966, Ser. No. 4,794

Term of patent 14 years

(Cl. D44—18)

FIGURE 1 is a top plan view of a dust pan, showing our new design;

FIGURE 2 is a right side elevational view;

FIGURE 3 is a front elevational view thereof;

FIGURE 4 is a bottom plan view thereof; and

FIGURE 5 is a rear elevational view thereof.

We claim:

The ornamental design for a dust pan, as shown.
